UNITED STATES PATENT OFFICE.

MARION R. SMITH, OF PORTLAND, OREGON.

DESIGN FOR A TOY DOG.

Application filed May 10, 1926. Serial No. 17,628. Term of patent 3½ years.

To all whom it may concern:

Be it known that I, MARION R. SMITH, a citizen of the United States, residing at Portland, county of Multnomah, and State of Oregon, have invented a new, original, and ornamental Design for a Toy Dog, of which the following is a specification, reference being had to the accompanying drawing, forming a part thereof, which is a perspective view of said toy.

I claim:

The ornamental design for a toy dog as shown.

MARION R. SMITH.
